FEEDING MEANS FOR WEAVING MACHINES

Rudolf Rossmann, Munich, Germany, assignor
to Tefag Textil Finanz A. G., Zurich, Switzerland

Application September 16, 1930, Serial No.
482,324, and in Germany September 23, 1929

12 Claims. (Cl. 139—125)

This invention has reference to feeding means for the weft or filler thread in that kind of looms or weaving machines in which the filler is fed to the fabric by means of special gripping or feeding instrumentalities, while the supply itself is retained outside of the shed, and it is intended to generally improve the operation of such devices and to devise means of an improved timing of the weft or filler introducing instrumentalities. In the devices of the general kind referred to the filler thread which is withdrawn from a stationary supply has to be secured to the gripping and thread introducing means, and accordingly to the weaving thread carrier before each pick of filler introducing step and it is then cut off, so that a length of thread corresponding to the width of the fabric is introduced. In the case of filler threads of different colors or of different kind having to be alternatingly introduced into the fabric it becomes necessary to provide means of individually securing these filler threads in a certain order to the gripping means or thread carrier. The attempts and suggestions made heretofore in this direction were generally unsatisfactory and failed to yield the desired uniform product. These and other objectionable features of the previous devices are avoided in this invention in a simple manner. The invention refers in view thereof to the feeding movement of different filler threads or wefts with relation to the thread introducing means, thread carrier or the like, so that the particular means of introducing the thread into the thread carrier, the beating up movement and the like are not particularly described in this specification.

In order to be able to operate with a plurality of changes of the pick it is necessary to provide for the alternating utilization of as many stationary filling spools as possible which are therefore generally arranged close to each other. They may be secured upon the frame of the loom or upon a separate frame or the like. The different picks or filling threads are led according to the invention from the stationary spools by way of guiding and tensioning members to a corresponding number of rocking feeding levers which admit of being controlled independently of each other in conformity with the pattern and which are moreover provided with thread clamping means adapted to take hold of the end of the particular filling threads. During the rocking movement of any one of the several individually controllable feeding levers the end of the particular filling thread is transferred to the gripping means or the thread carrier with the

simultaneous releasing of the clamp provided on the feeding instrumentality so that the filling thread is free to move through the clamping means, while the thread is introduced into the fabric. The clamp may comprise for this purpose two spring-acting clamping jaws and an additional clamping member which is so arranged as to become engaged between the said clamping jaws only at the time of the introduction of the filler. This regulation and the rocking of the feeding levers is preferably derived from the movement of the feeler needles by the action of levers and slides, the said needles being engaged with a stepwise fed paper ribbon or the like upon which the pattern is shown by perforations in the usual manner. In order to prevent injury of two or more simultaneously operated feeding levers in the case of wrong perforating of the paper ribbon, the feeling needles are connected with otherwise known ball-operated or roller-operated locking and arresting means. As a rule the transferring of the end of the filling thread from the thread clamp or the feeding lever to the shuttle is effected at a distance from the edge of the fabric which corresponds to at least the length of the thread carrier. As a result thereof, after the introduction of the web, there is obtained an undesirable projecting thread section between the severing point in the vicinity of the edge of the fabric and the thread clamping means of the feeder. In order to eliminate this difficulty the feeding levers according to the invention may be combined with a special reciprocating thread clamp which after the introducing of the pick or filler and the cutting off of the thread will take hold of the thus produced fresh end of the weft and will feed it to the thread clamp of the particular rocked feeding lever. The provision of such special reciprocating taking up clamps may however be dispensed with provided the feeding clamp, after having transferred the end of the filling thread to the thread carrier, is caused to follow the thread carrier during the introduction of the filler up to the severing point, that is to say, within proximity of the edge of the fabric, so that, after the cutting of the filler the freshly produced end of the filler may be immediately taken hold of by the feeding clamp.

In the drawings, Figure 1 is a diagrammatic sketch illustrating the relationship of the thread-rod, thread carrier and feeding clamp before the thread is fed to the carrier, and the manner of their attachment to the loom base.

Fig. 2 is a similar sketch showing their relationship at the time of threading the carrier.

- Fig. 3 is a similar sketch showing their relationship after the thread carrier has been sent through the warp shed and prior to the severing of the thread. 80
- 5 Fig. 4 is a similar sketch showing their relationship after severing of the thread and while rethreading the feeder clamp. 85
- Fig. 5 is a side elevation of the feed control and feeding mechanism and the manner of its attachment to the base of a loom. 90
- 10 Fig. 6 is an end view of Fig. 5. 95
- Fig. 7 is an end view of the radially assembled thread feeders showing how the feeding clamps are arranged with respect to the thread carrier. 100
- 15 Fig. 8 is a side elevation of the locking device to be used in connection with operation of the feeding mechanism. 105
- 20 Fig. 9 is a side elevation of the locking device showing one of the locking heads in operative position. 110
- 25 Fig. 10 is a detail view of one of the feeding clamps with the gripping jaws in an open position. 115
- Fig. 11 is a similar view with the jaws in a closed position. 120
- Fig. 12 is a plan view of Fig. 10. 125
- Fig. 7a is an end view of the assembled feeder clamps and their relationship to the individual bobbins, and common thread carrier. 130
- 30 Fig. 10a is a detail view of a feeding clamp and thread carrier, showing how the thread is transmitted to the carrier. 135
- 35 Fig. 12a is a plan view of Fig. 10 with additional impact means shown for the operation of the feeding clamp. 140
- 40 On the accompanying drawings an exemplification of the novel feeding means is shown diagrammatically, Figures 1, 2, 3 and 4 showing the entire arrangement seen from the side and in four different working positions. For the sake of clearness I have shown only one feeding instrumentality, one thread spool only and so on, but it should be understood that under actual 145 working conditions a plurality of groups of this kind are provided on a loom or weaving machine.
- 45 Figures 5 and 6 represent diagrammatically the means employed in this embodiment for the operation and control of the feeding lever. Figure 7 shows the manner of mounting the feeding levers. Figures 8 and 9 show a locking device to be used in connection with the operation of the feeding levers and in two different operating positions. 150
- 50 Figures 10, 11 and 12 illustrate the thread clamp provided on each feeding lever, the clamp being shown in vertical section in Figures 10 and 11 and in Figure 12 in horizontal section. Upon the machine frame *a* a plurality of feeding levers *c* (Figs. 1 and 7) are rockingly disposed in conformity with the particular number of filling threads of different kinds or of different color, the levers being provided at their free ends with clamping means for the purpose of gripping the end of a filling thread *e*. The bearings *c* of the feeding levers which are rockable in a vertical plane are arranged in a circle, as appears from Fig. 7 of the drawings, so that the several feeding levers are radially disposed. Fig. 7a shows the circularly arranged assemblage of the bobbin spool *b* and how the threads *e* run from each spool to the clamps *d* of the oscillating feeding lever *c*. Upon rocking the particular feeding lever *c* in the forward direction, the thread clamp mounted thereon is moved to the center of the circle of bearing means and is caused to become engaged with the weaving thread carrier *l* centrally disposed with relation to the bearings *c*. As illustrated in the co-pending application Serial No. 459,193, the thread carrier is provided with a wedge-shaped clamping member which takes the thread from the advanced feeding clamp. In this specification in Fig. 10a the thread transfer is shown to take place when an impact member *d* strikes the third resilient clamp *d*, *d*, which causes the wedge shaped head *d* to pass between the two jaws *d*, *d*, which are thereby forced apart and the thread *e* thus released. The thread is clamped to the thread carrier by pressing the wedge-shaped member *l* into thread carrier *l*. Before the lever *c* swings the jaws *d*, *d* are again closed by an impact member *d*. This forces the resilient jaws *d*, *d* rearwardly, so that then the two jaws *d*, *d* can act resiliently with respect to each other, engaging the thread *e*. Each filling thread *e* is delivered from a stationary filling spool *b* and is guided by the eyes *f*, *f*, the thread braking means *g* and the spring-acting thread tensioning means *n*, so as to enter the thread clamp *d* on the feeding lever *c*. However, the thread *e* may be guided in any other suitable manner by dispensing with one or more of the guiding and tensioning members. Above the weaving shuttle *l* which cooperates with a plurality of feeding levers *c* a horizontally movable movable rod *h* is disposed in the bearings *k* of the machine frame the front end of which is provided with a rockable thread clamp *i* for the taking hold of the fresh end of the filling thread obtained by the cutting of the pick and for the purpose of transferring this end into the upwardly oscillated feeding clamp *d*. 155
- 160 In the representation according to Fig. 1 the gripping thread carrier *l* is in the thread shooting position. The rod *h* which operates as the thread-taking up means has become sufficiently advanced for its thread clamping means *i* to become situated in the vicinity of the edge of the fabric and above the pointed end of the not yet inserted weaving thread carrier. The fabric itself is represented by the warp threads *m* which are shown as points in section through the shed. The feeding lever *c* is still in its lower inoperative position. The thread tensioner *n* is so arranged that it produces a slightly spring-acting tension upon the filling thread *e*, thereby keeping the thread *e* always taut. The tensioning means may however be dispensed with in certain cases within the scope of this invention. 165
- 170 In the position of parts according to Fig. 2 the feeding lever *c* is in the raised position with its thread clamp *d* in engagement with the thread carrier *l* which in this position takes hold of the end of the filling thread by means of the clamp or the like provided at its rearward end, but not shown in the drawings, while causing at the same time the opening of the feeding clamp *d* in a positive manner. Thereupon the weaving shuttle *l* is thrown through the shed and thereby draws the filling thread off from the filling spool *b* and causes it to pass through the open clamp *d* of the feeding lever *c*. The driving means of the thread carrier are not shown in the present invention, this being fully described in the co-pending application, Ser. No. 520,629. As shown in this application the thread carrier is worked in only one direction through the shed and is then again moved back to its starting position above or below the shed. The filling 175
- 180
- 185
- 190
- 195
- 200

thread *e* is then cut off in the usual manner adjacent the edge of the fabric. Thereupon the shed is closed and the filler is beaten up. Shortly before the cutting off of the filling thread the clamp *i* is swung downward by means not shown, so as to become adapted to take hold of the fresh end of filling thread obtained by the cutting. Thereupon the thread returning means which comprises the rod *h* and the additional thread clamp *i* is moving backward to the position shown in Fig. 4. In this position the clamp *i* of the rod *h* is opened and the end of the filling thread is now transferred to the particular raised feeding lever *c* the thread clamp *d* of which has been closed by means not shown in the drawings. This returning of the thread is aided by the thread tensioning means *n* as far as necessary, inasmuch as a certain, though not considerable pulling action is thereby produced upon the thread. The thread returning rod *h* is then forwardly reciprocated while its clamp *i* is opened and swung upwards and the weaving thread carrier *l* is restored to its shooting position and the feeding lever *c* is returned to its position of rest shown in Fig. 1.

The thread clamp provided on each of the rockable feeding levers *c* comprises two clamping jaws *d*₁, *d*₂ (Figures 10 to 12) which are engageable with the end of the filling thread and are supported on spring-acting arms *d*₃, *d*₄. An additional locking jaw *d*₅ is provided at right angle with relation to the clamping jaws *d*₁, *d*₂ and which is likewise supported by a spring-acting arm *d*₆. When the filling thread is transferred to the weaving shuttle *l* (Fig. 1) the two clamping jaws *d*₁, *d*₂ are positively spread apart, so that the additional jaw *d*₅ by its spring-action is adapted to lockingly enter between the clamping jaws *d*₁, *d*₂, as appears from Fig. 12 of the drawings. The filling thread *e* is then disengaged and is free to loosely pass through the thread clamp during the insertion of the weft. As soon as the thread restorer of returning means *h* occupies the position according to Fig. 4 the locking jaw *d*₅ is forced back by the action of a stop *d*₈, as shown in Fig. 12a, so that the two other jaws *d*₁, *d*₂ may again assume their clamping position in engagement with the fresh end of filling thread by the action of their spring-acting supporting arms.

The automatic selection and the control of the several feeding levers *c* is effected in the similar manner as in the case of the exchange of shuttles or of the adjustment of shuttle boxes in the ordinary looms, that is to say by the use of an endless band of paper *t* (Figures 5 and 6) which is perforated in conformity with the changing of filling thread and which is given a stepwise movement. One manner in which this stepwise movement may be obtained is by the pin-wheel and cam disc mechanism (Fig. 5) a pin-wheel *u*¹ is provided on the axis of the roller *u* which is advanced for definite short steps by means of a rotatable cam disc *u*², but any other known means of obtaining such a stepwise movement may be used. Above the band of paper *t* a plurality of vertically disposed feeler needles *q* are arranged the number of which conforms to the number of the feeding levers *c* and of the filling spools *b*. The feeler needles are in engagement with the surface of the band *t* and are dropping down somewhat by their weight or by spring action, as soon as a perforation of the paper band becomes engaged with the feeler. Each of said feeler needles *q* carries an ear or an

eye *q*, in which the free left hand end of a rod *v* is guided. Upon its lower side this rod has a stop *v*₁ which upon the descent of the particular feeler needle *q* cooperating therewith is moved into the path of a reciprocating arresting bar *v*₂. The other right hand end of the rod *v* is connected to a two-armed lever *w* which is pivotally secured at *w*₁ by a stud or the like on the frame *a* of the machine. The other end of the lever *w* is in engagement with an approximately semi-circular slide *x* which is likewise rotatably mounted to the frame *a* of the machine. The section *x* of the annular slide carries an ear-like extension *x*₁ which is slotted with an inclined slot *x*₂ in which the left hand end of a rod *o* is guided the right hand end of which is linked to the corresponding feeding lever *c*. In view of the fact that each feeding lever *c* corresponds to a sliding member *x*, a rod *v* and a feeler needle *q*, not only the feeler levers *q* and the rods *v*, but also the ring-shaped slide *x* are arranged parallel with and close to each other. The rods *o* are also disposed parallel to each other but around a circle, inasmuch as the feeding levers *c* are circularly arranged. In view thereof the 100 ear-like extensions *x*₁ provided on the several sliding rings *x* and the inclined slots *x*₂ are likewise arranged so as to be staggeringly disposed with relation to each other, as shown in dotted lines in Fig. 6 of the drawings. Each rod *o* is provided with a groove or a cranked portion *o*₁ which becomes engaged with the segment-like knife *p*₁ of a reciprocating bar *p* upon the raising of the rod *o*, the said bar *p* being horizontally and displaceably guided in the bearings *p*₂ provided in the machine frame. The segment-shaped knife *p*₁ is of a size to extend over a plurality of adjacently disposed rods *o*, so that several of such rods *o* may be alternately engaged with one and the same knife *p*₁.

As soon as a feeler needle *q* has entered a hole of the paper band *t* and of the roller *u*, the stop *v*₁ is caused to move into the path of the stopping or arresting bar *v*₂ as the result of a slight downwardly rocking movement of the bar *v*. The bar *v*₂ on moving to the right carries the bar *v* with it and produces the rotation of the corresponding sliding ring section *x* connected therewith in the direction of the arrow. The inclined slot *x*₂ provided in the sliding ring section is thereby caused to move the rod *o* engaged therewith somewhat upwards, so that the groove or crank portion *o*₁ thereof is engaged with the segment-shaped knife *p*₁ of the bar *p*. As a result thereof the corresponding feeding lever *c* is rocked upwards upon the forward movement of the bar *p* and segmental knife *p*₁ by the action of the rod *o* being then in the operative position, and in this position the corresponding thread clamp *d* is made to become engaged with the weaving thread carrier. In this position the feeding lever *c* with the thread clamp *d* will remain, until the filling thread has been completely inserted and the fresh end of the filling thread has been again secured at the thread clamp. Thereupon the bar *p* is returned and by its segmental knife *p*₁ it causes the feeding lever *c* to be rocked back to its position of rest. Immediately thereafter the stopping bar *v*₂ is moved back to its left-hand terminal position and is disengaged from the stop *v*₁ of the rod *v* which latter thereupon is returned to its initial position by spring action as for instance by a spring *y* acting upon the lever *w* together with said corresponding lever *w* and with the sliding ring section *x*. By means not shown herein the feeler needle is

raised together with the rod v_1 , so that the stop v_1 is out of the way at the next advancing movement of the stopping or arresting bar v_2 .

The feeler needles q are bent at their upper ends and are provided with a blade-shaped head r . The heads of all the feeder needles are disposed closely adjacent each other as appears from Figures 8 and 9, so that they will guide each other. Underneath the heads r a box or container z is mounted with a number of balls of rolls s , corresponding to the number of heads and ordinarily disposed in cavities z_1 of the bottom the relative position of which is so arranged with relation to the heads r that the balls are disposed alternately or staggeringly with relation to the blades of the heads r . If a feeler needle q drops into a hole of the paper band t its head r will at the same time penetrate into a row of balls, forcing the balls sideways out of their bearing cavities, as seen more clearly in Fig. 9. The balls will then lock the other head r , inasmuch as they will now be disposed directly underneath the blades. Thus only one feeler needle is in position to occupy the lowest point of movement. If two feeler needles should descend simultaneously, thus for instance as a result of faulty perforation or on account of damaging of the paper band, their heads are arresting each other already upon entering the rows of balls. The feeler needles are thereby prevented from occupying their low position which is necessary for the operation of the stops v_1, v_2 , so that the simultaneous and injurious rocking of two feeding levers is sure to be avoided.

The invention has been described herein only in its broad features and it will have to be understood that it is open to modifications and changes to suit varying conditions of operation, and without thereby deviating from the principles of the invention as set forth in the appended claims.

40. I claim:—

1. In a thread-feeding device for looms, a stationary weft furnishing bobbin, a rockable feeding lever spaced therefrom, gripping means on said lever, engageable with the weft, a reciprocable gripping thread carrier engageable with the gripping means in a certain position of the lever, and additional lengthwise movable gripping means, engageable and disengageable with the weft and with the said gripping means.

56. 2. In a thread-feeding device for looms, a stationary weft furnishing bobbin, a rockable feeding lever spaced therefrom, gripping means on said lever, a fabric, a gripping thread carrier, engageable with the gripping means in the swung-out position of the lever, and movable through said fabric, additional lengthwise reciprocable gripping means, engageable with the weft-ends at the side of the fabric and with the gripping means and adapted to take hold of the

60. free end of the severed weft and to deliver same to the gripping means, and tensioning means for the weft intermediate the lever and the bobbin.

65. 3. In a thread-feeding device for looms, a stationary weft furnishing bobbin, a rockable feeding lever spaced therefrom, gripping means on said lever, and a spring acting operating jaw for the gripping means, a tissue fabric, a thread carrier intermediate the fabric and the gripping means, and engageable with the gripping means in the swung-out position of the lever, and reciprocatingly movable through the fabric, and additional gripping means lengthwise reciprocable in parallelism with the thread carrier, and engageable at the side of the fabric with the severed weft and with the gripping means and

adapted to deliver said weft into the gripping means.

4. In a thread-feeding device for looms, a plurality of stationary weft-bobbins, carrying tissue-forming wefts, a plurality of feeding levers spaced therefrom corresponding to the bobbins, gripping means on said levers, means for releasing said gripping means for free passage of the weft through said gripping means, individual rocking means for each of said levers, a movable control pattern, and feelers engaging said pattern and movable with relation thereto and operatively connected to said rocking means, locking means for the feelers, a tissue-fabric, a reciprocable gripping thread carrier intermediate the fabric and the gripping means and engaging said gripping means in a certain position of the corresponding levers, and movable through the fabric.

5. In a thread-feeding device for looms, a plurality of stationary weft-bobbins, carrying tissue-forming wefts, a plurality of feeding levers for the wefts, spaced from the bobbins, gripping means for the weft on said levers, a tissue-fabric, a gripping-thread carrier reciprocable through the fabric and disposed intermediate the same and the gripping means, and engageable with said means, a movable control pattern, a plurality of feeler-levers corresponding to the number of bobbins and of the levers, rocking means for the levers, spring-operated link-connection between the feeler levers and the rocking means, arresting means for said link-connection, controlling extension bars, adjacently disposed and connected to the feeder levers, pointed terminal portions on said bars and a plurality of roller-balls below said terminal portions, and normally disposed intermediate thereof, and sideways yieldable upon the descent of any of such bars.

6. In a thread-feeding device for looms, a plurality of stationary weft-carrying and distributing bobbins, a tissue-fabric, a gripping thread carrier at one side of the fabric and reciprocable therethrough, rockable feeder-levers for said thread carrier, gripping means on the levers, engageable with the thread carrier, and carrying and guiding the wefts from the bobbins to the thread carrier, a control pattern, a plurality of parallel feelers, corresponding to the bobbins and the levers and engaging the pattern, and movable with relation thereto, a plurality of adjacently disposed, substantially semi-circular, steering rings, spring-actuated link-connection between the steering rings and the feelers, laterally and lengthwise movable controlling bars connected to said rings and linked to the feeder-levers, and holding means for said controlling bars.

7. In a thread-feeding device for looms, a plurality of stationary weft-carrying and distributing bobbins, a tissue fabric, a gripping thread carrier at one side of the fabric and reciprocable therethrough, rockable feeder-levers for each of said bobbins and said thread carrier, gripping means on said levers, carrying and guiding the wefts and engaging the thread carrier in the erect position of the levers, a movable control pattern, a plurality of feelers, corresponding to the bobbins and to the levers engageable with the pattern, and axially movable, a plurality of substantially adjacently disposed, substantially semi-circular slides, link-connection between said slides, and the corresponding feelers, arresting means for said link-connection, axially mov-

- able steering rods, linked to the levers, and slot-connection of each of said rods with the corresponding slide, and reciprocable holding means, engaging said rods in a certain position thereof, 5 and reciprocable holding means for the link-connection of the slides. 80
8. In a thread-feeding device for looms, a plurality of stationary weft-carrying and distributing bobbins, a plurality of corresponding feeder-levers, rockingly and radially disposed, a freely reciprocating thread carrier centrally disposed with relation to said levers, gripping means on said levers, engaging the thread carrier in certain positions of the levers, means for repositioning the end of a thread in said gripping means, a tissue-fabric, engageable by said thread carrier, and rocking and controlling means for said levers. 85
9. In a thread-feeding device for looms, a plurality of stationary weft-carrying and distributing bobbins, a plurality of corresponding feeder-levers, rockingly and radially disposed, gripping means on said levers carrying and guiding the weft of the corresponding bobbin, a thread carrier centrally disposed with relation to said levers, and engageable with the gripping means of the operated feeder-lever, a plurality of substantially adjacently disposed, substantially semi-circular slides, a slotted guiding projection on each of said slides, and staggeringly disposed with relation to each other, operating rods in said slotted projections pivoted to corresponding feed-levers, reciprocable arresting and securing bars, engageable with said rods, a step-wise movable pattern, and movable feelers, engaging said pattern and spring-actuated link-connection between said feelers and the semi-circular slides, and locking means for the link-connection. 90
10. In a thread-feeding device for looms, a stationary weft supply bobbin, a rockable feeding lever, gripping means on said lever engageable with the weft and a freely reciprocating gripping thread carrier including means to coat with said gripping means and additional lengthwise movable gripping means, engageable and disengageable with the weft and with said gripping means for repositioning of the weft in the latter. 95
11. In a multiple thread feeding device for looms, a plurality of radially spaced, rockable feeding levers, thread gripping means on said levers engageable with the weft from individual weft supply bobbins, a common, freely reciprocating, gripping thread carrier to coat with said gripping means and control means for controlling the order in which the gripping means coat with the thread carrier and means for repositioning the thread in the gripping means after placing of the weft in the warp shed. 100
12. In a multiple thread feeding device for looms, as defined by claim 11, a locking mechanism operatively connected to the control means for preventing the simultaneous rocking of more than one feeding lever. 105
